UNITED STATES PATENT OFFICE.

WALTER E. LOWELL, OF NEW YORK, N. Y., ASSIGNOR TO NATIONAL BISCUIT COMPANY,
OF NEW YORK, N. Y., A CORPORATION OF NEW JERSEY.

MACHINE FOR STACKING AND PACKAGING BAKERY PRODUCTS.

1,279,562.

Specification of Letters Patent. Patented Sept. 24, 1918.

Application filed June 21, 1916. Serial No. 104,855.

To all whom it may concern:

Be it known that I, WALTER E. LOWELL, a citizen of the United States, and a resident of New York, in the county of New York 5 and State of New York, have invented certain new and useful Improvements in Machines for Stacking and Packaging Bakery Products, of which the following is a specification.

10 My invention relates to a machine for stacking and packaging bakery products such as biscuits, cakes, cookies, or the like.

The object of the invention is to produce a machine in which the products are received at one end and delivered at the other end properly arranged in cartons. More 15 specifically the invention contemplates a machine which at one end receives pans containing products to be packed; which has

20 mechanism for removing the products from the pans and mechanism for stacking the products on edge in continuous rows; and which has carton filling mechanism for filling the stacked products into cartons. Properly timed driving mechanisms are provided 25 for the conveying, stacking and packaging mechanisms.

A machine embodying the various features of my invention is shown on the accompanying drawings in which—

Figure 1 is a plan view,

Fig. 2 is a sectional view on plane 2—2, Fig. 1,

Fig. 3 is an enlarged sectional view on plane 3—3, Fig. 1,

Fig. 4 is a sectional view on plane 4—4, Fig. 3,

Fig. 5 is a sectional view on plane 5—5, Fig. 3,

Fig. 6 is an enlarged sectional view on plane 6—6, Fig. 2,

Fig. 7 is an enlarged sectional view on plane 7—7, Fig. 1, and

Fig. 8 is an enlarged perspective view of 45 one of the releasing slides for controlling the charging of biscuits into the cartons.

The supporting structure for the machine is in the form of a long table 10. At one end of the table is a vertical framework 11 forming a conveyer passageway for pans *p* containing products to be packaged. Conveyer belts 12 and 13 extend through the bottom of the conveyer passageway for receiving the pans, these belts being provided with pan 50 abutment fingers 12' and being driven by

sprocket wheels on shafts 14 and 15, one of the shafts being driven by a chain belt 16 from a main shaft 17 which carries the belt pulley 18. The pans *p* are shifted from the conveyer belts 12 and 13 to the belts 19 and 20 which engage sprocket wheels on the shafts 15 and 21, the belts 19 and 20 extending diagonally.

Before the pans reach the lower ends of the inclined belts the biscuits, cakes or other products are removed therefrom to a conveyer belt 22 which passes around the pulleys 23 and 24 on shafts 23' and 24', the belt 22 extending almost full width of the machine between side plates 25 and 26 supported on the table.

The mechanism for scraping and removing the biscuits or other products from the pans is clearly shown in Figs. 1, 2, 6 and 7. A plurality of scraper blades 27 are arranged 75 in a transverse row and are pivoted at their inner ends on the rod 28 extending between the front ends of the side plates 25 and 26 between which the belt 22 travels. Normally the blades rest near their front ends on a rod 29 which extends between the ends of levers 30 and 31 pivoted at an intermediate point at the upper ends of brackets 32 and 33 which rise from the table top, as clearly indicated in Figs. 6 and 7. The inner ends of 80 the levers are connected by links 34 and 35 with the inner ends of weight levers 36 and 37, these levers being pivoted at an intermediate point to the brackets 32 and 33 and at their outer ends carrying the rollers 38 and 39.

Provision is made, as by means of weights 40, for normally over-balancing the lever mechanism in order to cause the rod 29 to be normally raised sufficiently to hold the outer ends of the scrapers 27 above the path 95 of an approaching pan *p* and to hold the rollers 38 and 39 in the path of the oncoming pans. With this arrangement, as a pan *p* approaches its advance edge will first encounter the rollers 38 and 39 to effect swing 100 of the levers 36 and 37, thereby raising the links 34 and 35 and causing swing of the levers 30 and 31 to lower the rod 29 away from the scrapers to permit the scrapers to drop into the pan immediately inside the 105 front edge of the pan. The biscuits, cakes, or other products *c* are then scraped from the pan and travel down the scrapers onto the belt 22. The outside scrapers preferably have the vertical guide flanges 41 for pre- 110

venting escape of biscuits as they travel over the scrapers. The conveyer belt 22 may be driven in any suitable manner. As shown, a chain 42 engages sprocket wheels on shaft 5 21 and the pulley shaft 24'.

The biscuits or other products rest flat on the conveyer belt 22, and before they are charged into cartons they are stacked on edge into rows. Extending transversely of the 10 machine alongside the inner end of the conveyer belt is the guide plate 43 which is supported at its ends by the side walls 25 and 26. Guide ridges 44 extend parallel with the sides 25 and 26 and are spaced between them 15 to form passageways 45 for the biscuits, the ends 46 overhanging the inner end of the belt 22 and being pointed in order to better guide the biscuits into the passageways. Behind the plate 45 the table top 47 has the slots 48 therethrough between the guides 44, and through these slots project the upper runs of 20 belts 49, these belts having each blocks 50 secured thereto with inclined upper faces, as clearly shown in Figs. 2 and 3. The passageways 45 are of slightly greater width than 25 the diameter of the biscuits, and as the biscuits travel along with the belt 22 they are guided into the passageways by the points 46 and the rows of biscuits travel down the 30 plate 43 between the guides and onto the blocks 50 of the respective belts, the blocks being each of a length to accommodate one biscuit. Each of the belts is mounted on 35 sprocket wheels 51 and 52 on transverse shafts 53 and 54, the shaft 53 being connected by drive belt 55 with the shaft 21, the belts 49 traveling at the same rate as the belt 22.

At the right of the belt slots 48 the table 40 top 47 has the troughs 56 and 57 cut therein, these troughs forming continuations of the channels between the guides 44. The width of the passageways 45 between the guides 44 is only slightly larger than the diameter 45 of the cakes in order to allow the cakes to travel freely. The slots 48 through which the belts project are just wide enough to allow passage of the blocks 50 therethrough and the cakes are therefore of greater diameter 50 than these slots. The troughs 56 and 57 are no wider than the slots and therefore when the belt blocks pass downwardly through the inner ends of the slots 48 the cakes thereon will be caught by the edges 58 55 adjacent the slots and will be shifted by the descending blocks along these edges until they engage with the floors 59 of the troughs. Centrifugal force will also aid in shifting the cakes from the blocks to the troughs and 60 during shift of the cakes from the belt blocks to the troughs they will be tilted from flat position to position on edge and each cake will be brought up against the back of the preceding cake so that the stacks are 65 shifted to the outer ends of the troughs.

The troughs 57 alternate with the troughs 56 and are longer than the troughs 56. At the end of each trough 56 there is a discharge slot 60 through the table top and at the end of each trough 57 there is a similar discharge 70 slot 61, the slot 60 being in one transverse row and the slot 61 in an adjacent transverse row. In accordance with my invention each slot is normally closed by a slide plate 62. Extending transversely under the 75 table top and secured to the under side thereof of adjacent the opposite ends of the slots 60 are slide-ways 63 and 64 for receiving the end tongues 65 and 66 of the plates for the slots 60. Likewise, slide-ways 67 and 68 are 80 provided for the tongues of the plates for the slots 61. The plates for the slots 60 are secured together by side bars 69 and 70 which are connected at one end to a cam arm 71 which extends into the cam groove 72 of a 85 cam 73 mounted on shaft 74 which is journaled in the bearing brackets 75 and 76. Likewise, the slider plates for slots 61 are connected by side bars 77 and 78 which are connected to a cam arm 79 which extends 90 into cam slot 80 of the cam 81 also mounted on shaft 74. The cams are so adjusted that when the slider plates under slots 60 are moved in one direction those under slot 61 will be moved in the opposite direction. The 95 shaft 74 may be driven in any suitable manner. As shown, the bevel gear 82 thereon meshes with a gear 83 on the shaft 54. The tops of the slider plates are level with the floors of the troughs, the cross-section of 100 which at the slots is preferably rectangular. To hold the cakes on edge yieldable abutment disks 84 and 85 are provided in the troughs 56 and 57 respectively, the disks being held yieldingly against the advance 105 ends of the cake rows by springs 86. As the cake rows are being added to and travel along the troughs toward the discharge slots, the disks exert sufficient pressure to prevent toppling over of the cakes, and they 110 are finally shifted onto the slide plates over the discharge slots. Below each slot a frame 87 is supported from which extend downwardly the side plates 88 and 89 and the end plates 90 and 91, the plates deflecting 115 inwardly a distance and the side plates being somewhat longer than the end plates. As will be presently shown, these plates enter into cartons to hold the cartons open for the reception of cakes which are discharged 120 through the discharge slots when the slide plates are shifted from underneath the slots. Each slide plate has at its ends the blades 92 and 93 respectively which are in front of the front edge of the plate and extend upwardly. When one row of plates is in position to close the respective discharge slots the blades will be out of the slots to permit passageway for cakes onto the plates. However, when the plates are slid to expose the 125 130

discharge slots, these blades are shifted onto the slots at the ends thereof, one set of blades coming into position in front of the respective abutment disks 84 and 85 and the other set coming into position in front of the cake rows remaining after the ends of the rows have been discharged through the slots. This is clearly shown in Figs. 3 and 4, the dotted lines in Fig. 3 showing the normal 10 positions of the blades, and the full lines showing the blades in the slots with the blades 92 in position in front of the disks 85 to prevent pressure of the disks against the cakes during discharge and with the 15 blades 93 in front of the cake row sections in advance of the sections which are being discharged. After discharge the slide plates will be shifted back to slot-closing position and the abutment disks will be shifted by 20 their springs into engagement with the ends of the rows which are released from the blades 93 and return to normal position.

In Figs. 3, 4 and 5, the mechanism is shown for bringing cartons into position to receive the discharged cakes. Supported 25 on the table structure in vertical registration below each slot are four guides 94, 95, 96 and 97, these guides being shown secured to the cross beams 98 on the table structure 30 and strengthened by braces 99. A carton elevator frame 100 is provided in connection with each set of guides and is rectangular and has the vertical sides 101 and 102 connected below by a yoke 103. At the corners of the sides are secured vertical guide tongues 104, 105, 106 and 107 respectively having sliding engagement in the guides 94, 95, 96 and 97 respectively. At their inner ends the sides 101 and 102 are bent inwardly 40 at right angles to form abutment flanges 108 and 109, and below the tops of these flanges horizontal shelves 110 and 111 extend inwardly from the elevator sides and form seats for cartons. Extending through 45 the elevator frames between the sides thereof are the conveyer belts 112, each belt serving to convey cartons to and away from each of the frames. The belts travel with pulleys 113 and 114 on shafts 115 and 116 50 respectively, the shaft 115 being driven by belt 117 which engages with a sprocket on the shaft and with a sprocket on the shaft 53 (Fig. 2).

Below the elevator frames for the discharge 55 slots 60 is the cam shaft 118, and below the elevator frames for the discharge slots 61 is the parallel shaft 119. Depending from the yoke of each elevator frame is a bearing bracket 120 journaling a cam roller 121. 60 Each cam roller of the elevator frames below discharge slots 60 co-operates with a cam disk 122 on shaft 118, and each of the cam rollers of the elevator frames below discharge slots 61 co-operates with a cam disk 65 123, the cams being shaped to effect ver-

tical reciprocation of the elevator frames. However, the relative arrangement of the cams 122 and 123 is such that the elevator frames under discharge slots 60 will be raised while those under discharge slots 61 70 are being lowered, and vice versa. The shafts are connected by a drive chain 124 and one of the shafts is connected by a drive chain 125 with the shaft 115. The cams are all alike and their cam contour is such that 75 when an elevator frame is down and the cam starts to rotate it will first raise the frame a short distance, will then hold the frame in this shifted position for a period, will then quickly raise the frame to the top of its 80 guides, will then hold it at the top for a period, and will then restore it to its lower position. In Figs. 3 and 4, the elevator frames under discharge slots 60 are shown in their lower positions and the frames under 85 discharge slots 61 are in their upper positions. When the frames are in their lower positions the shelves 110 and 111 therein will be below the top runs of the belts 112. By the time the cartons reach the end flanges 90 108 and 109 of the frames, the frames will have been raised by their cams to bring the shelves into engagement with the cartons to release them from the belts and then the frames are rapidly raised to their upper positions, the guide plates 88, 89, 90 and 91 95 engaging at the inner sides of the unfolded side and end cover sections of the carton to hold them spread apart while the cakes are being discharged into the cartons, the 100 timing of the various drive mechanisms being such that the discharge plates over the raised cartons will be shifted to open the discharge slots to permit the released cakes to drop into the cartons. After filling of the 105 carton the elevator frames are lowered and just before they reach their lowermost positions the filled cartons will reach the belts from which they are taken as soon as the frames reach their lowermost positions to 110 bring the tops of the abutment flanges 108 and 109 below the upper runs of the belts 115 below the cartons, and the released cartons will then travel with the belts to be discharged therefrom. The feeding of cartons to the belts is so timed that each elevator frame will raise a carton from the belt to be filled and will then carry it back to the belt before the next carton enters the frame.

After the filled cartons are carried out of 120 the elevator frames by the belts their cover sections are folded to closed position and the package is sealed.

I do not, of course, desire to be limited to the exact construction, arrangement and operation shown as changes and modifications are no doubt possible which would still come within the scope of the invention.

I claim as follows:

1. In a machine of the class described, the 120

combination of a supporting table having a trough in its upper surface, means for delivering biscuits or similar bakery products edgewise to said trough and for shifting the delivered biscuits along the trough in a row, a movable bottom for the end section of said trough normally closed to receive a predetermined number of biscuits, means for periodically moving said bottom to release the collected biscuits, and conveyer mechanism below the table top controlled to carry containers into position below the trough end to receive discharged biscuits and to then carry away the filled containers.

2. In a machine of the class described, the combination of a supporting table having a trough in its upper surface, means for delivering biscuits or similar bakery products edgewise to said trough and for shifting the delivered biscuits along the trough in a row, a movable bottom for the end section of said trough normally closed to receive a predetermined number of biscuits, means for periodically moving said bottom to release the collected biscuits, an elevator below the trough end, conveyer mechanism for conveying containers to said elevator, and means for periodically raising said elevator to bring the container therein into position below the trough end to receive discharged biscuits and for then lowering said elevator to bring the filled containers back to the conveyer mechanism.

3. In a machine of the class described, the combination of a supporting table having a trough in its upper surface, means for delivering biscuits or similar bakery products edgewise to said trough and for shifting the delivered biscuits along the trough in a row, a movable bottom for the end section of said trough normally closed to receive a predetermined number of biscuits, means for periodically moving said bottom to release the collected biscuits, an elevator below the trough end, a conveyer belt for conveying containers to said elevator, means for raising said elevator to bring the container therein into position below the trough end to receive discharged biscuits, and means for lowering said elevator to bring the filled containers back to the conveyer belt whereby the container can be carried away from said elevator.

4. In a machine of the class described, the combination of a supporting table having a trough in its upper surface, means for delivering biscuits or similar bakery products edgewise to said trough and for shifting the delivered biscuits along the trough in a row, a movable bottom for the end section of said trough normally closed to receive a predetermined number of biscuits, means for periodically moving said bottom to release the collected biscuits, an elevator below the

trough end, a conveyer traveling continuously below said elevator for conveying containers to be filled, means for periodically raising said elevator to receive a container from the conveyer and to bring it into position below the trough end to receive discharged biscuits, and for lowering the elevator to return the filled containers to the conveyer to be carried away from the elevator.

5. In a machine of the class described, the combination of a supporting table having a trough in its upper surface, means for delivering biscuits or similar bakery products edgewise to said trough and for shifting the delivered biscuits along the trough in a row, a movable bottom for the end section of said trough normally closed to receive a predetermined number of biscuits, means for periodically moving said bottom to release the collected biscuits, a continuously traveling conveyer below the table top for conveying containers to be filled, and means for periodically removing a container from said conveyer and bringing it into position below the trough end to receive discharged biscuits and to then restore the filled container to the conveyer.

6. In a machine of the class described, the combination of a supporting table having a plurality of troughs in its upper face, means for delivering biscuits or similar bakery products edgewise to said troughs and for shifting them in rows along said troughs, one of said troughs being longer than the other, a discharge slot at the end of each trough, a bottom closure for each slot normally closed to receive a predetermined number of biscuits, means for effecting alternate operation of said closures to open said discharge slots alternately, and means associated with each discharge slot for bringing a container thereunder to receive discharged biscuits when the slot is opened.

7. In a machine of the character described, the combination of a supporting table having one set of parallel troughs of one length and a second set of troughs of a greater length and alternating with the troughs of the first set, means for delivering biscuits or similar bakery products edgewise to said troughs and for shifting them along said troughs in rows, the troughs of one set having bottom outlet openings at their ends and the troughs of the other set having similar bottom outlet openings at their ends, closure means for the first set outlets and closure means for the second set outlets, said closure means normally closing the outlets to receive predetermined numbers of biscuits, means for alternately moving said closure mechanisms to open the outlets, and means below said outlets for supporting the containers to receive the biscuits as they are discharged through said outlets.

8. In a machine of the character described, the combination of a trough, means for delivering biscuits or similar bakery products edgewise to said troughs and for shifting them along the trough in a row, a yieldable abutment engaging the advancing end of said row to keep the biscuits edgewise and together, a false bottom for the end section of said trough normally closed to receive a predetermined number of biscuits at the advancing end of said row, means for periodically shifting said false bottom to release the biscuits thereon, and means for supporting a container to receive the discharged biscuits.
9. In a machine of the character described, the combination of a trough, means for delivering biscuits or similar bakery products edgewise to said troughs and for shifting them along the trough in a row, a yieldable abutment engaging the advancing end of said row to keep the biscuits edgewise and together, a false bottom for the end section of said trough normally closed to receive a predetermined number of biscuits at the advancing end of said row, means for periodically shifting said false bottom to release the biscuits thereon, means for supporting a container to receive the discharged biscuits,
- 10 and a stop blade on said false bottom moved thereby into the biscuit row to check the advance of said row during discharge of biscuits.
11. In a machine of the character described, the combination of a trough, means for delivering biscuits or similar bakery products edgewise to said troughs and for shifting them along the trough in a row, a yieldable abutment engaging the advancing end of said row to keep the biscuits edgewise and together, a false bottom for the end section of said trough normally closed to receive a predetermined number of biscuits at the advancing end of said row, means for periodically shifting said false bottom to release the biscuits thereon, means for supporting a container to receive the discharged biscuits, and stop blades at the sides of said bottom moved into the trough when the bottom is shifted to release biscuits, one of said blades being then in position to check the flow of biscuits and the other being in front of said abutment to prevent return thereof while the biscuits are being discharged.
12. In witness whereof I hereunto subscribe my name this 16th day of June, A. D. 1916.

WALTER E. LOWELL.
